United States Patent Office

Des. 195,998
Patented Aug. 13, 1963

195,998

MICROSCOPE STAND

Karl Auböck, Vienna, Austria, assignor to C. Reichert
Optische Werke Aktiengesellschaft, Vienna, Austria

Filed Dec. 26, 1961, Ser. No. 68,077

Term of patent 14 years

(Cl. D57—1)

FIG. 1

FIG. 1 is a perspective view of the microscope stand showing one side thereof; and

FIG. 2 is another perspective view of the microscope stand showing the other side thereof.

The essential features of the design reside in the portion shown in full lines on the drawing.

I claim:

The ornamental design for a microscope stand, as shown and described.
